Application September 30, 1948, Serial No. 52,032

6 Claims. (Cl. 126—116)

1

This invention relates to heating devices and more particularly to a heating device of the internal combustion type in which a combustible fuel is burned. Although the illustrated embodiment of the present invention has been shown and described as one intended to burn hydrocarbon fuel in liquid phase, the invention is not to be limited thereto, for fuels in gaseous or vaporous phase could be used.

Heating devices of the internal combustion type have been previously proposed and used as heaters for motor vehicles, airplanes, and the interiors of buildings of various sizes. Such devices as have been heretofore proposed have generally consisted of a spray element for injecting liquid fuel such as gasoline, diesel oil and other hydro-carbons in droplets into a combustion chamber. Various igniting devices have been proposed to ignite the injected fuel with varying success.

Considerable difficulty has been experienced in igniting the fuel particularly at low temperatures and at high altitudes. This difficulty has plagued the industry for many years and although various solutions have been advanced heretofore, no one solution has completely solved the problem of starting the heater and maintaining combustion of the fuel at low temperatures and at the altitudes at which present day airplanes operate. Although internal combustion heaters for use in aircraft present problems not presented by heaters designed for use in motor vehicles such as passenger cars, trucks and busses, nevertheless the latter type heaters, particularly in cold weather, have not generally been entirely successful. Failure of ignition of the fuel-air mixture is the most frequent cause of dissatisfaction.

The present invention provides an internal combustion heater in which the fuel-air mixture is easy to ignite even at temperatures well below 0° F. and at low pressures corresponding to high altitudes. As is well known, the ignition of liquid fuels becomes increasingly difficult as the temperatures of the liquid fuel and combustion air and ambient pressures are decreased. At least a part of the difficulty arises from the strong dependence of vapor pressure of such liquid fuels upon temperature. At relatively low temperatures, spontaneous vaporization may occur at such a low rate that the resulting air-fuel mixture is so lean that combustion of the mixture may be extremely difficult or even impossible. For instance, it has been found that ignition of the fuel in an aircraft heater may be easily brought about when the temperature of the fuel and com-

2

bustion air is relatively high but that the flame is often extinguished by the cold fuel droplets and cold inlet air as the aircraft ascends into altitudes of colder temperatures and lower pressures where little, or no, spontaneous vaporization of the fuel takes place.

Furthermore, at high altitudes because of the low atmospheric pressures, the combustion air supplied to a combustion chamber of heaters, of the type herein disclosed, from the ambient atmosphere is less dense than at sea level and, as is well known, combustion of even a static system is more difficult to maintain where the density of the fuel-air mixture is relatively low. 10 The geometries of the heater of the present invention and the action of the injector-burner therein used produces a more stable combustion system which is not as adversely affected by low atmospheric pressures as previously proposed 15 combustion systems of prior heaters.

It will also be seen that the lower density of the fuel-air mixture necessarily calls for a greater volume flow of combustion air to maintain a given thermal output and the required increased velocity of the combustion air often extinguished the flame in prior heaters. In the heater of the present invention the velocity of the combustion air entering the combustion chamber has little, if any adverse effect on the combustion flame so 20 that the difficulties had with prior heaters is not experienced with the heater of this invention.

The present invention provides means for insuring a high rate of vaporization and lean fuel-air mixtures are thus eliminated. To bring about 25 this feature of the present invention, liquid fuel is heated to rapidly produce fuel vapor, which vapor is further heated as it admixes with a portion of the combustion air which is also warmed. The resulting fuel vapor-air mixture is easily 30 ignited and as the fuel, the vapors thereof, and the fuel vapor-air mixture can be continuously warmed in the operation of the heater there is no danger of the main combustion flame being extinguished as in prior heaters.

40 In the now preferred embodiment of the heater of the present invention, liquid fuel is collected in a well contiguous to a fuel injector and a heating element mounted in the well vaporizes the liquid fuel collected therein, and further heats the fuel vapor formed to increase admixing of the fuel vapor with combustion air as well as to heat the mixture formed. Ignition of the heated fuel vapor-air mixture can now be easily brought 45 about by any means desired although in one embodiment of the heater herein shown the mixture

is ignited by the portion of the heating element disposed above the surface of the liquid fuel held by the well.

The ignition of the mixture creates a pilot flame, which impinging against the fuel injector, rapidly increases the temperature thereof, which results in better vaporization of the incoming fuel. The fuel injector is comprised of a hollow vessel at least one wall of which is permeable by the liquid fuel. The liquid fuel passing through the permeable wall is caused to vaporize and this when mixed with combustion air forms a combustible mixture which is easily ignited by the pilot flame previously created as above described. A main combustion flame is thus established at the fuel injector, which as will now be seen also serves as a burner. The flame established at the injector-burner further heats the same and liquid fuel supplied to the interior of the hollow vessel forming the injector-burner is consequently heated and vaporization of this fuel is had actually within the injector-burner. Thus the injector-burner itself furnishes fuel to the combustion chamber in the physical state most conducive to efficient burning. With the main combustion flame now established at the injector-burner, which serves also as a flame holder, the heating and igniting element can be deenergized.

In another embodiment of the invention, the fuel vapor-air mixture, although warmed by the heating element mounted in the well, is ignited by a separate igniting element mounted adjacent to the well. In this form of the invention, a hood-like shield or guard is mounted over the well and serves to trap and guide the mixture to the igniting element. The ignition of the mixture, as in the earlier mentioned embodiment of the present invention, heats the injector-burner and produces vaporization of the liquid fuel not only at the surface of the latter but within the same as well.

Ignition of the fuel vapor-air mixture produced at the injector-burner is quickly brought about and the main combustion flame thus created at the burner, which also serves as a flame holder, further heats the fuel supplied thereto to produce even more rapid vaporization of the fuel.

The ignition means may be formed as a part of the injector-burner by embedding in at least one wall member and preferably the porous or foraminous member a resistance element which, when energized, will heat the wall member to a temperature sufficient to vaporize and ignite the resultant fuel vapor-air mixture formed contiguous to the surface of the burner. If desired, a separate igniting element may be mounted adjacent the injector-burner for igniting the combustible mixture formed by the commingled fuel vapor and air surrounding the burner.

The injector-burner, in all embodiments illustrated, serves further as a flame keep-alive for preferably the same is formed of a material having a low heat capacity and thermal conductivity. Thus, if for any reason the main combustion flame is extinguished at the injector-burner, re-ignition is immediately brought about as the fuel vapors passing through the permeable wall of the injector-burner are admixed with combustion air at the exterior surface of the injector-burner which is at a temperature sufficiently high to ignite the mixture created at the surface.

Other features and advantages of the present invention will be apparent from the following detailed description of the illustrated embodiments of the present invention, particularly when taken

in connection with the accompanying drawing, in which:

Figure 1 is a perspective view of one embodiment of the heater of the present invention partly in phantom;

Figure 2 is a sectional view of the heater shown by Figure 1;

Figure 3 is a section taken along 3-3 of Figure 2;

Figure 4 is a perspective view of the heating and igniting element of the heater of Figure 1;

Figure 5 is a top plan view of the heating and igniting device shown in Figure 4;

Figure 6 is a longitudinal, sectional view of the heating and igniting device;

Figure 7 is a sectional view of a modified form of the injector-burner of the heater of the present invention;

Figure 8 is a view similar to Figure 2 but showing a modified embodiment of the heater of the present invention;

Figure 9 is a section taken along line 9-9 of Figure 8;

Figure 10 is a fragmentary sectional view of the heater of the embodiment shown in Figures 8 and 9; and

Figure 11 is a view similar to Figure 7 but showing a still further modified form of the injector-burner.

The heater of the present invention in one embodiment herein illustrated, referring now to the drawing and more particularly to Figures 1 through 6, comprises an outer shell or casing 10 formed at one end with an inlet 11 for air to be heated. This air may be supplied by a compressor or air pump forming a part of the heater or may be air from a ram duct particularly if the heater is used on an airplane. The outer shell is formed at the end opposite to said inlet with an opening or register 11a for discharging into the space to be heated air which has been passed over the exterior surface of the combustion chamber 12. To increase the heat transfer from the wall of the chamber 12 the exterior surface of the same is provided with a plurality of longitudinally extending fins 13 which may be cast or molded integrally with the chamber wall. If desired, however, the fins 13 could be separately formed and then subsequently secured to the exterior surface of the chamber wall by some conventional process such as welding or brazing.

The combustion chamber 12 itself may be formed by any conventional forming or fabricating process or processes, but should be of a material which will withstand the high temperatures produced by the burning fuel-air mixture. Although the size and shape of the chamber may vary depending upon the intended use of the heater, in the form of the invention illustrated, the chamber 12 is an elongate substantially cylindrical shaped member open at one end thereof and formed with an exhaust port 12a adjacent the opposite end through which exhaust gases are discharged into the atmosphere. A transverse wall 14 is held across the open end by a substantially dome-shaped closure element 15 bolted or otherwise secured to the edge face of the open end of the chamber.

The transverse wall 14 and closure dome 15 form a plenum chamber 16 into which combustion air is forced from a source of air under pressure. This source may comprise a ram, although in the form of the invention herein shown, air under pressure is furnished to the plenum chamber by a small compressor or air pump 17 car-

ried by the outer shell 10 by a suitable bracket 18. A duct 19 leads air from the discharge end of the compressor through the dome closure 15 and into the plenum chamber. It should now be seen that combustion air, after burning of the fuel has commenced, is warmed by the air flowing around duct 19, this air having been heated in passing over the combustion chamber 12. In addition, the wall 15 of the plenum chamber is traversed by the heated air just prior to its exit through the register 11a, thus further heating the inlet combustion air in chamber 16.

The transverse wall 14 is formed with a relatively large opening 21 located adjacent the upper marginal portion thereof. The wall is provided with a vane 22 which is so positioned that air passing through the opening 21 is directed by the vane downwardly and over a fuel injecting device 23.

The fuel injecting device comprises a small vessel or receptacle, the walls of which are at least poriferous in part, which may take various forms depending upon the flame pattern desired. This vessel may be formed of numerous materials so long as the specific fuel to be burned will permeate at least a portion of the wall members or readily pass through the same. The material may be porous, that is, one with such interstices or foramina that permeation by the fuel is possible, or the material forming the walls of the vessel may be impervious and rendered porous or foraminous by small openings or channels formed through the walls of the vessel.

The material used to form the vessel or receptacle 23 could be a porous metal formed by the techniques of powder metallurgy or one of a number of porous ceramics. Where a porous material, either metal or ceramic, is used the interstices of the material should be of such size that the liquid will, by capillary flow or because of pressure on the liquid, pass through the walls of the vessel.

It should be noted here that the entire vessel need not be formed of a porous material so long as a portion of a wall is permeable by the fuel. Thus, for example, the vessel might be formed in part of a material impervious to the fuel and in part by a porous material which would permit passage of the fuel. The wall portion permeable by the fuel could consist of a reticulated plate or screen of a suitable metal or other material permanently mounted across an opening in one or more wall members of the vessel.

The fuel injecting vessel 23 may be mounted within the combustion chamber 12 by any means desired although, in the form of the invention illustrated, the vessel is held in place by a small duct or conduit 24 forming a fuel line connecting the vessel to a source of fuel (not shown). It will be seen, referring to Figure 2, that the line-forming duct passes through aligned openings formed in the outer shell 10 and a boss 25 carried by the wall of the combustion chamber and is held against longitudinal or axial movement by split, tapered plugs 26, threaded into tapped openings formed at opposite ends of the boss 25. If desired, or found necessary, the conduit 24 may be provided with a protective sheath or other means for protecting the same from the temperature to be expected.

Fuel, under a pressure varying in proportion to the porosity of the material forming the walls of the vessel 23, is delivered into the vessel, the interior of which may be provided with means for distributing the fuel over the interior sur-

face of the walls thereof and consequently the exterior surface of the same. These means may take the form of internal vanes 27 oppositely projecting from the adjacent inner wall surfaces of the vessel. The vanes 27, as will be apparent, distribute the fuel over the interior surfaces of the walls of the vessel and thus insure the desired distribution of the fuel over the exterior surfaces of the vessel.

As is well known, the ignition of liquid fuels becomes increasingly difficult as the temperatures of the liquid fuel and combustion air are decreased. Part of the difficulty arises from the strong dependence of vapor pressure of such liquid fuel upon the temperature. At low temperatures spontaneous vaporization may occur at such a low rate that the resulting air fuel mixture is so lean that combustion of the mixture, or the initiation thereof, may be impossible.

This difficulty is eliminated by the present invention for the fuel is heat vaporized and the fuel vapors heated before and during the ignition thereof. As the fuel is heated the rate of vaporization is rapid and lean mixtures are eliminated and further as the vapors are heated after vaporization, ignition thereof is easily brought about.

In the embodiment of the invention now being described, referring again to the drawing, fuel 30 passed through the walls of the vessel 23 is ignited by a novel fuel heating, vaporizing, and igniting element 28, best illustrated in Figure 6 of the drawing. This element comprises a heating element 29 of a suitable resistance wire coiled 35 about a sleeve 31 of an insulation material, such as asbestos, circumscribing a hollow metallic plug 32 formed with an enlarged head 33 at the lower end thereof. The upper surface of the head 33 may be formed with an annular groove or slot in 40 which the lower edge of the sleeve 31 may be suitably anchored. One end of the wire forming the heating element 29 is permanently grounded to the head of the plug at 34. The other end passes through the bore of the plug and is intended to be connected to a source of current, not shown. The portion of the wire disposed within the bore of the plug is spaced from the wall thereof by suitable insulating element 35.

The plug 32 carrying the resistance or heating element 29 is threadedly mounted in a tapped opening centrally formed in a cylindrical boss 36 integral with the wall of the combustion chamber 12. To facilitate mounting of the plug within the boss, the headed end of the plug is formed with an annular flange 37 the peripheral surface of which may be knurled as indicated at 38.

The depth of the head 33 is such relative to the length of the boss 36 that the inner portion of the head projects beyond the inner surface of the wall of the combustion chamber and is threadedly received by a tapped opening formed in the bottom wall of a well 39 forming a part of a dish-like member 41. The member 41 is partially held to the wall of the combustion chamber by the threaded engagement between the head of the plug and the tapped opening in the bottom wall of the well 39 and partially by locating bolts 42 insertable through openings formed in the boss 36 and adapted to be threaded into tapped openings in the well 39, respectively. The bolts 42 beside holding the member 41 to the wall of the combustion chamber also locate the member to align the opening in the lower wall of the well with the opening in the boss 36. Thus in assembling the member within the combustion

chamber the bolts 42 are passed through the openings in the boss 36 after which the projecting ends are threaded into the opening in the wall of the well 39. The latter openings are so located relative to the large threaded opening in the lower wall of the well 39 that reception of the bolts 42 in their respective opening will properly align the large opening of the well with the opening formed in the boss 36. The plug can now be threaded into the bore formed by the aligned openings to complete the mounting of the member 41.

To permit easy access to the plug the outer shell 10 is provided with an opening slightly larger in diameter than the flange of the plug. This opening is formed so as to align with the opening in the boss 36 receiving the plug and is normally closed by a closure element 43 carrying a grommet 44 of some suitable insulating material for passing the resistance wire or lead of the heating element 29.

For reasons which will be hereinafter apparent, a gasket 45 may be mounted between the lower wall of the well 39 and the wall of the combustion chamber, as well as between the flange 37 and the under surface of the boss 36.

The member 41 in addition to the well 39, includes a relatively large but shallow pan 46 positioned so as to catch fuel dropping from the injection device formed by the vessel 23. The lower wall of this pan is formed or provided with troughs or elongate depressions 47 of varying lengths radially extending outwardly from the well 39. These troughs slope inwardly from their outer ends to the well so that fuel falling onto the pan gravitates into the well.

In operation, fuel is delivered to the injection device or vessel 23 under a pressure sufficient to cause the fuel to pass through the porous wall member or members of the vessel. In this initial stage of operation liquid fuel drops onto the pan 46 and flows through the troughs 47 to the well 39. The heating and igniting element 29, having previously been energized, heats the fuel held by the well thereby causing the same to vaporize. Fuel vapor rising from the surface of the fuel held by the well passes upwardly along the portion of the heating and igniting element above the surface of the fuel. This fuel vapor admixes with air as it travels upwardly along the element and is heated thereby to form an inflammable mixture which is easily ignited by the upper portion of the glowing wire of the element.

It will thus be seen that the element 29 actually performs three functions; first, the lowermost portion, that is, the portion immersed in the liquid fuel held by the well vaporizes this fuel; second, the intermediate portion of the element heats the fuel vapors rising from the surface of the fuel; and third, the upper portion ignites the heated fuel vapor-air mixture as it rises and flows upwardly along the element. It is thus obvious that three separate elements could be used if desired. It has been found however that the single element under most conditions of use will properly function to bring about the results enumerated above.

It can be mentioned here that the element 29 could be formed of a plurality of short lengths of resistance wires of different operating characteristics suitably joined end-to-end to form a single path of resistance which would operate at different degrees of heat. Thus, for example, the upper portion of the element could be formed of a resistance wire which, when energized, would

attain a higher temperature than the remainder of the element.

To insure that the fuel vapors pass upwardly around the element, and are further heated thereby, a guard 48 in the form of an apertured or perforated sleeve may be mounted to the pan. The majority of the apertures provided in the guard are to admit air into the same although the primary purpose of the apertures provided at the lower edge of the guard is to insure that fuel caught by the pan 46 and flowing along the troughs 47 can pass through the guard into the well 39. This guard, as best shown in Figure 6, forms a flue or chimney which draws the heated fuel vapors upwardly around the element 29 and also prevents combustion air delivered into the combustion chamber through the opening 21 from carrying the vapors away from the element.

It should be noted that combustion air in addition to that delivered through the opening 21 may be necessary. In such event an additional opening can be provided in the wall 14 of such as the opening shown at 49. It is to be understood that further openings can be provided if found necessary because of the fuel-air ratio used or flame pattern desired in the combustion chamber proper.

The ignition in the region of the ignitor 28 and combustion of the fuel-air mixture over the well 39 serves as a pilot flame to initiate combustion of fuel on the surface of the fuel injecting device 23. Once combustion at the injector-burner 23 has been established, there is little likelihood of the flame being extinguished. This is due in part to the fact that fuel vaporization and air-fuel vapor intermixing takes place within the burner formed by the vessel 23 or at the exterior surface of the same or both locations. In short, the burner itself furnishes fuel to the combustion chamber in the physical state most conducive to efficient burning, that is, as a vapor. Thus, there is no necessity for pre-carburetion of the fuel nor for altering the physical status of the fuel, such as atomization, prior to delivery of the fuel to the combustion flame zone.

The vessel also functions as an efficient flame holder for, referring now to Figure 2, combustion air is directed against the back surface of the vessel adjacent the opening 21 and swirls around the front or downstream surface. The translational velocity of the air moving over the front surface of the vessel is relatively low although the absolute velocity may be high. Such a moving air pattern is favorable to a stable flame and a flame front attaches and holds to the downstream face or surface of the vessel, whence the translational component of the air velocity carries the flame into the main combustion chamber.

The vessel also will function as a flame keep-alive particularly where a material such as a ceramic having a low heat capacity and thermal conductivity is used to form the vessel. If a metal is used to form the vessel, a button or even a ring of ceramic can be mounted to the vessel to increase the flame keep-alive action. Such a keep-alive is shown at 51 in Figures 2 and 3.

In this connection it can also be pointed out that flame keep-alives can be mounted to the pan 46 if desired. There is shown at 52 one form of a keep-alive which can be used with the pan. This keep-alive, somewhat T-shaped, is formed of any material desired, which has a low thermal capacitance and can be mounted to the pan by fusion or other mechanical connection. It should be obvious now that the pan 46 itself

should be of a material having a low thermal capacitance. Also the heat path between the pan and the wall of the combustion chamber should be kept to a minimum to reduce heat losses to the wall of the chamber.

It should also be understood that the pan 46 prevents fuel from striking the relatively cold wall of the combustion chamber and thence being swept out of the exhaust as in many of the previously proposed heaters. Once combustion is initiated a large portion, if not all, of the fuel caught by the pan is readily vaporized and burned from the pan. With a high rate of fuel supply, the pan may serve as an auxiliary vaporizing and flame-holding surface, as well as a keep-alive, in a much more effective way than the relatively cold wall of the combustion chamber.

The B. t. u.'s supplied by the heater of the present invention may be varied by independent or simultaneous variation of the rate of air or fuel flow, either or both of which may be varied by conventional means which have not been shown. It has been found that the permissible over-all air-fuel ratio may vary over an extremely wide range. Furthermore, combustion with any air-fuel ratio between 10:1 and 200:1 is smooth and extremely efficient.

It has also been found that the velocity of combustion air supplied to the combustion chamber can be varied within an extremely wide range of velocities. The air velocity may be that for just perceptible motion for example one (1) foot per second or it may be as high as will allow combustion within the combustion chamber. As the velocity of the air may be varied obviously the pressure head under which the air is supplied to the combustion chamber may also be varied.

There is shown in Figure 7 a section of a modified form of the combined fuel injector and burner 23. In the form of the burner there shown the vessel 54 is formed in the same manner and of the same materials as was the vessel 23. The section of Figure 7 is taken along a plane normal to the plane of the section shown by Figure 2 and as the interiors of the vessels 23 and 54 are identical the showing of Figure 7 also can be used to more clearly illustrate the position and function of the vanes 27.

The injector and burner formed by the vessel 54 differs from the previously described vessel 23 in that a downwardly projecting funnel-like element 55 is integrally formed with the lowermost wall section of the vessel 54. This funnel-like element 55 is formed with an opening 56 at its lower end which serves as a discharge vent for liquid fuel during the initial operation of igniting the fuel. As liquid fuel enters the vessel 54 and flows downwardly therethrough it is collected by the element 55 and then discharged through the opening 56 directly onto the heating element and into the well 39.

Accordingly, the vapor forming and fuel vapor-air admixing steps of the method of igniting the fuel is speeded by the use of the injection burner of Figure 7 for it is not necessary for the liquid fuel to pass through the walls of the burner and be collected and then channeled by the pan 41 into the well 39.

There is shown in Figures 8 through 10 a modified form of the heater of the present invention in which many of the elements are the same as elements in the embodiment of the invention earlier described. For the sake of brevity, elements in the embodiment of the invention shown

in Figures 8 through 10, identical in form and purpose with elements in the heater of Figures 1 through 6, will not be further described but will merely be given the same reference characters.

5 In the embodiment of the heater of the present invention shown in Figures 8 through 10, the injector-burner is the same as the burner 54 shown in Figure 7 and is mounted within the combustion chamber 12 by the conduit 24 as is the injector-burner 23. The funnel-like element 55 of the injector-burner 54 projects downwardly through an opening formed in a hood-like shield 58 carried by the pan 41. This shield 58 extends upwardly over the well 39 and resistance element 29 and at least at the one side thereof, extends outwardly and upwardly over an igniting element 59 mounted to the wall of the combustion chamber 12. Although the igniting element 59 may take various forms, in the illustrated embodiment of the heater herein shown, this element comprises a glow coil consisting of a coiled length of resistance wire 61 carried by a suitable support 62 of some insulating material. The one end of the wire 61 is grounded to a metallic threaded plug 63 to which is mounted the support 62, while the opposite end of the wire is fastened to a lead to permit the wire to be connected to a source of current. The element 59 is mounted to the wall of the combustion chamber 12 by threading the plug 63 into a tapped opening formed in a boss 64 formed integrally with the wall of the combustion chamber. To facilitate mounting of the element 59 the plug 63 is formed at the one end thereof with a head 66 provided with a plurality of tool-engaging surfaces.

20 In this embodiment of the present invention the coil 29 is intended to operate primarily as a vaporizing element and may therefore be so operated as to attain a lower temperature than the coil of the earlier described embodiment of the invention. As the glow coil 59 is an igniting element the temperature of the wire 61 obviously must be such as to ignite the mixture formed by the heated fuel vapors arising from the coil 29 and commingling with combustion air under the hood or shield 58.

25 The shield 58 may take various forms so long as it protects the glow coil 59 from cooling effects produced by incoming combustion air entering the combustion chamber through the opening 21. Although the guard 48 previously described has been shown in the illustrated embodiment of the form of the invention now being described, it has been found that this guard is not always necessary in this embodiment of the invention and may be removed if desired.

30 The heater of the embodiment of Figures 8 through 10 operates substantially in the same manner as does the heater of the earlier described embodiment of the invention. Liquid fuel entering the injector-burner 54 flows downwardly therethrough and is discharged through the opening 56 directly on to the heating and vaporizing element mounted within the well 39. As has been previously explained, the fuel readily vaporizes as it comes into contact with the coil 29 and as the fuel vapors pass upwardly over the same they are further heated by the coils and form a combustible mixture as they commingle with combustion air flowing under the hood or shield 58. As this combustible mixture flows upwardly over the igniting coil 59 it is ignited and the resulting flame heats the injector-burner 54 to raise the temperature of the same to a degree

11

of heat sufficient to vaporize the liquid fuel supplied to the same. The combustible mixture formed by the fuel vapors flowing from the injector-burner admixes with the combustion air to produce a primary combustible mixture which, when ignited by the burning fuel-air mixture just described, forms a primary combustion flame at the injector-burner. This primary combustion flame further heats the injector-burner so that, as in the earlier described embodiment, the burner itself furnishes fuel to the combustion chamber in the physical state most conducive to efficient burning, that is, as a vapor.

It should be obvious that the injector-burner 54, in this embodiment of the invention now being described, also functions as a flame holder in the same manner as does the injector-burner 23. The injector-burner 54 also can be supplied with a keep-alive similar to the keep-alive 51 of the injector-burner 23.

There is shown in Figure 11 a still further modified form of the injector-burner. In this embodiment, the burner comprises a dish-like member 68 open at the one side thereof. The open side of the member is closed by a transverse wall element comprising a pair of plates 69 and 71 held in a facewise engagement. The adjacent or contacting faces of the plates are each formed with half-round grooves which form, when the plates are mounted across the opening of the member 68, a spirally-shaped course, circular in cross-section, for receiving a suitable electrical resistance wire 72. This wire is connected to a source of current (not shown) through a lead 73 carried within a protecting sheath 74 which may be supported by the conduit 24.

The plates 69 and 71 forming the transverse wall closing the open side of the member 68 are porous or foraminous so that liquid fuel supplied to the interior of the injector-burner will flow, either by capillary action or because of pressure on the fuel, through the wall formed by the plates 69 and 71. This material, of which the plates are formed, preferably has a low heat capacitance, as well as a low thermal conductivity, so that the heat transferred thereto by said resistance wire 72 will cause the wall to attain a relatively high temperature. The heat of the wall will also raise the temperature of the remainder of the burner and the combined action of the relatively hot wall and the heated remainder of the burner will readily vaporize the fuel permeating the wall. The fuel vapors issuing from the wall will readily mix and commingle with combustion air flowing past and around the burner to form a combustible mixture ignitable by either the relatively hot wall of the injector-burner or by a separate ignition element mounted adjacent the injector-burner.

Although, in the illustrated embodiment of the injector-burner shown in Figure 11, only the wall formed by the plates 69 and 71 is shown as foraminous, it is to be understood that all wall members may be formed of a material which will permit flow of the fuel and its vapors.

Although the now preferred embodiments of the present invention have been illustrated and described herein, it is to be understood that the invention is not to be limited thereto, for it is susceptible to changes in form and detail within the scope of the appended claims.

We claim:

1. In an internal combustion heater, means forming a sealed horizontally disposed combustion chamber having inlet and outlet passageways at opposite ends, blower means connected

12

said inlet passageway for supplying a flow of air through said combustion chamber, a fuel conduit extending into said chamber near the end having the inlet passageway, a fuel vaporizing burner having a substantially vertical wall disposed transverse of said air flow and supported on said conduit, fuel conducting means arranged to conduct fuel from said conduit to a downstream face of said wall exposed to said combustion chamber, said wall being adapted to permit liquid fuel to drip therefrom, a fuel igniting structure located below and out of contact with said burner wall and embodying a pan positioned to collect raw fuel dripping from said burner when initially delivered thereto by said conduit and when said burner is cold, an electrically energizable glow coil extending into said pan in position to heat to vaporization the fuel collected therein, and means for shielding said vaporized fuel adjacent to said glow coil from said flow of air while supplying an amount thereto sufficient to form a combustible mixture, said shield directing the flame into heat transfer relationship to the burner wall whereby the fuel is vaporized on the downstream face thereof and burned when mixed with the air flowing through said combustion chamber.

2. In an internal combustion heater, means forming a sealed horizontally disposed combustion chamber having inlet and outlet passageways at opposite ends, blower means connected to said inlet passageway for supplying a flow of air through said combustion chamber, a fuel conduit extending into said chamber near the end having the inlet passageway, a fuel vaporizing burner having a substantially vertical wall disposed transverse of said air flow and supported on said conduit, fuel conducting means arranged to conduct fuel from said conduit to a downstream face of said wall exposed to said combustion chamber, said wall being adapted to permit liquid fuel to drip therefrom, a fuel igniting structure located below and out of contact with said burner and embodying a pan positioned to collect raw fuel dripping from said burner when initially delivered thereto by said conduit and when said burner is cold, an electrically energizable glow coil extending into said pan in position to heat to vaporization the fuel collected therein, means for shielding said vaporized fuel adjacent to said glow coil from said flow of air while supplying an amount thereto sufficient to form a combustible mixture, said shield directing the flame into heat transfer relationship to the burner whereby the fuel is vaporized on the downstream face thereof and burned when mixed with the air flowing through said combustion chamber, and means for igniting said vaporized mixture above said pan.

3. In an internal combustion heater, means forming a sealed horizontally disposed combustion chamber having inlet and outlet passageways at opposite ends, blower means connected to said inlet passageway for supplying a flow of air through said combustion chamber, a fuel conduit extending into said chamber near the end having the inlet passageway, a hollow fuel vaporizing burner having at least one fuel pervious substantially vertical wall disposed transverse of said air flow adapted to permit liquid fuel to drip therefrom and supported on said conduit with the downstream face of said wall in position to support a flame, said conduit being arranged to deliver fuel to the interior of said burner, a fuel igniting structure located below and out of con-

tact with said burner embodying a pan positioned to collect raw fuel dripping from said burner when initially delivered thereto by said conduit and when said burner is cold, an electrically energizable glow coil extending into said pan in position to heat to vaporization the fuel collected therein, and means for shielding said vaporized fuel adjacent to said glow coil from said flow of air while supplying an amount thereto sufficient to form a combustible mixture, said shield directing the flame into heat transfer relationship to the burner whereby the fuel is vaporized on said downstream face and burned when mixed with the air flowing through said combustion chamber, the portion of said glow coil out of contact with said raw fuel being disposed in position to ignite said vaporized mixture.

4. In an internal combustion heater, means forming a sealed horizontally disposed combustion chamber having inlet and outlet passageways at opposite ends, blower means connected to one said passageway for producing a flow of air through said combustion chamber, a fuel conduit extending into said chamber near the end having the inlet passageway, a flat fuel vaporizing burner supported on said conduit and having a wall disposed in a vertical plane transverse to said flow of air and adapted to permit liquid fuel to drip therefrom, means for directing fuel from said conduit to the downstream face of said wall so that vaporization and burning will occur on the downstream side of the burner relative to said flow of air, a fuel igniting structure located below said burner and embodying a pan positioned to collect raw fuel dripping from the bottom of said burner which is delivered thereto from said conduit when said burner is cold, an electrically energizable means mounted within the combustion chamber and located in such relation to said pan as to heat to vaporization the fuel collected therein, means mounted within said combustion chamber adjacent to said energizable means for shielding said vaporized fuel from said flow of air while supplying an amount of air thereto to form a combustible mixture, and a second energizable means located adjacent to said pan for igniting said mixture.

5. In an internal combustion heater, means forming a sealed horizontally disposed combustion chamber having inlet and outlet passageways at opposite ends, blower means connected to one said passageway for producing a flow of air through said combustion chamber, a fuel conduit extending into said chamber near the end having the inlet passageway, a flat fuel vaporizing burner supported on said conduit and having a wall disposed in a vertical plane transverse to said flow of air and adapted to permit liquid fuel to drip therefrom, means for directing fuel from said conduit to the downstream face of said wall so that vaporization and burning will occur on the downstream side of the burner relative to said flow of air, a fuel igniting structure located below said burner and embodying a pan positioned to collect raw fuel dripping from the bottom of said burner which is delivered thereto from said conduit when said burner is cold, an electrically energizable means mounted within the combustion chamber and located in such relation to said pan as to heat to vaporization the fuel collected therein, and means mounted within said combustion chamber adjacent to said energizable means for shielding said vaporized fuel from said flow of air while supplying an amount of air thereto to form a combustible mixture, 75

said shield directing the flame from the igniting structure into heat transfer relationship to the burner whereby the fuel delivered thereto is vaporized, mixed with air and burned so that no further fuel is delivered to said pan, said energizable means being a glow coil which is partially immersed by the fluid collected in the pan for heating said fluid to vaporization, the part extending above the fluid being available to ignite the vaporized mixture.

6. In an internal combustion heater, means forming a sealed horizontally disposed combustion chamber having inlet and outlet passageways at opposite ends, blower means connected to one said passageway for producing a flow of air through said combustion chamber, a fuel conduit extending into said chamber near the end having the inlet passageway, a flat fuel vaporizing burner supported on said conduit and having a wall disposed in a vertical plane transverse to said flow of air and adapted to permit liquid fuel to drip therefrom, means for directing fuel from said conduit to the downstream face of said wall so that vaporization and burning will occur on the downstream side of the burner relative to said flow of air, a fuel igniting structure located below said burner and embodying a pan positioned to collect raw fuel dripping from the bottom of said burner which is delivered thereto from said conduit when said burner is cold, an electrically energizable means mounted within the combustion chamber and located in such relation to said pan as to heat to vaporization the fuel collected therein, means mounted within said combustion chamber adjacent to said energizable means for shielding said vaporized fuel from said flow of air while supplying an amount of air thereto to form a combustible mixture, said shield directing the flame from the igniting structure into heat transfer relationship to the burner whereby the fuel delivered thereto is vaporized, mixed with air and burned so that no further fuel is delivered to said pan, said energizable means being a glow coil which is partially immersed by the fluid collected in the pan for heating said fluid to vaporization, the part extending above the fluid being available to ignite the vaporized mixture, said pan sloping toward a well therein through which the glow coil extends which heats the initial flow of oil as it collects thereabout, said glow coil being removable from said pan exteriorly of the combustion chamber, vanes extending from said combustion chamber longitudinally thereof, and an outer casing surrounding said chamber and engaging the outer ends of said vanes for forming longitudinal air passages extending from one to the other end of the combustion chamber.
